UNITED STATES PATENT OFFICE.

FRANCIS M. DIGMAN AND HARRY E. DIGMAN, OF WITT, ILLINOIS.

CAR-COUPING.

1,116,251.

Specification of Letters Patent.

Patented Nov. 3, 1914.

Application filed June 13, 1913. Serial No. 773,484.

To all whom it may concern:

Be it known that we, FRANCIS M. DIGMAN and HARRY E. DIGMAN, citizens of the United States, residing at Witt, in the county of Montgomery and State of Illinois, have invented new and useful Improvements in Car-Couplings, of which the following is a specification.

The present invention relates to improvements in couplers for cars, and especially for mine cars.

In carrying out our invention, it is our purpose to provide a coupler in the form of a ball and socket joint which is so arranged upon the cars as to prevent the accidental uncoupling thereof and which are also so arranged that the members of the coupler will be sustained in longitudinal alinement with each other regardless of the angular relation of the cars to which the couplers are secured. We also aim to provide a coupler of this class wherein the members may be easily and quickly connected and also whereby the said members may be easily and quickly disconnected when desired.

A still further object of the invention is the provision of a coupler which shall embody the desirable features of simplicity in construction, cheapness to manufacture, ease of application, and accuracy and surety in operation.

With the above and other objects in view, the improvement resides in the construction, combination and arrangement of parts set forth in the following specification and falling within the scope of the appended claims.

In the drawings: Figure 1 is a view of two cars connected in accordance with our improvement, Fig. 2 is a view illustrating the manner of connecting or disconnecting the coupler members, parts being shown in section, Fig. 3 is a detail perspective view of one of the couplers, and Fig. 4 is a similar view of the co-acting coupling member.

While in the accompanying drawings, the improvement is illustrated in connection with two mining cars, it is to be understood that the device is not to be thus limited in its useful capacity, as the same may be applied to other vehicles, if desired.

In the drawings, 1 and 2 designate the cars, each of which has its end sills provided with one or more loosely connected links 3, and each of the links engages with an eye 4 provided upon each of the coupler members 6 and 5 respectively.

The member 5 is in the nature of a sleeve or thimble, the toe end of which being provided with the eye. The bore 8 of the thimble terminates with a shoulder 9 that is provided adjacent the mouth of the thimble, so that the open mouth proper of the thimble comprises a reduced rounded opening which communicates with the bore 8. The thimble has a lower flat face which is slotted longitudinally, as at 10, the said slot entering the reduced flange mouth of the thimble and the opposite end of the slot terminates in a rounded opening 11 which enters the bore 8.

The second coupler member 6 has its face centrally formed with a longitudinally extending stem 12 which terminates in a spherical or ball head 13. The face of the coupler 6 is in the nature of a flat peripheral rounded member or flange 14, and it is upon this portion that the eye 4 is formed. The flat face of the thimble 5 is provided with the substantially key-hole shaped opening formed by the slot 10 and its annular terminal 11 has its end rounded, as at 15, to the outer face of the thimble.

The links 3 provide a sufficient slackness between the coupler members to permit of the coupler member 5 being raised to an angle, as illustrated in Fig. 2 of the drawings, and the spherical head 13 of the coupler 6 being inserted through the enlarged opening 11 of the key hole slot to arrange the said head within the bore 8 while the length of the shank 12, between the spherical head 13 and the flange 14 is equal to the thickness of the walls provided by the slot 10, so that the member 6 may be moved longitudinally toward the end of the member 5 until its spherical head contacts with the shoulder 9, when the flat inner face of the body portion of the coupler 6 may be swung over the rounded lower edge 15 of the coupler 5 and the flange 14 of the coupler 6 brought into tight frictional engagement with the outer ends of the coupler 5. The stem 12 is of sufficient length and the shoulder 9 is spaced a sufficient distance from the end of the coupler 5 to permit of the coupling members being retained in frictional engagement and in longitudinal alinement when the said coupling members are associated regardless of the slack of the links or the angular arrangement of the links when the cars are rounding curves, so that it is impossible for the couplers to be

come accidentally disassociated, and in order to uncouple the cars, it is absolutely necessary that the coupler 5 be tilted upwardly to the position illustrated in Fig. 2, before the members of the coupler can be disconnected.

From the above description, taken in connection with the accompanying drawings, the simplicity of the device as well as the advantages thereof will, it is thought, be perfectly apparent to those skilled in the art to which such inventions appertain without further detailed description.

Having thus described the invention, what we claim is:

In a car coupler, two members each adapted to be loosely connected to a car, one of said members comprising a thimble having its open end reduced to provide a shoulder between the said end and the bore of the thimble, said thimble having a longitudinal flat surface which is rounded to the open end of the thimble, the said flat surface having a longitudinal slot which communicates with the shouldered end of the thimble, the said flat surface being provided with an annular opening of a greater area than the slot and communicating with the slot, the sec-

ond coupler comprising a member having an integral flat flange which is centrally formed with a longitudinal shank which has spherical head formed on its end the shank being of a length equaling the width of the walls of the bore provided by the slot and the distance between the shoulder and the outer face of the thimble member, whereby the flange and head will frictionally engage with the bore and flat surfaces of the thimble and the head passed through the annular opening in the bore and moved toward the shoulder, and also whereby the said head and flange will frictionally engage between the shoulder and the end wall of the sleeve when the second coupler member is brought into longitudinal alinement with the thimble to sustain the said second coupler member in such alinement with the thimble.

In testimony whereof we affix our signatures in presence of two witnesses.

FRANCIS M. DIGMAN.
HARRY E. DIGMAN.
